LOUIS B. MALINOWSKY AND CLYDE W. KIRK, OF PATTERSON, CALIFORNIA.

CHIMNEY THIMBLE.

1,414,367.

Specification of Letters Patent.

Patented May 2, 1922.

Application filed November 19, 1921. Serial No. 516,336.

To all whom it may concern:

Be it known that we, LOUIS B. MALINOWSKY and CLYDE W. KIRK, citizens of the United States, and residing in the city of Patterson and State of California, have invented new and useful Improvements in Chimney Thimbles, of which the following is a specification, reference being had to the accompanying drawing.

10 This invention is a chimney thimble for stove pipes, and the object is to provide a device of this kind, formed from a single piece of sheet metal, and which will include means both for locking the thimble into the 15 chimney flue and for locking the stove pipe into the thimble.

In the drawing:

Figure 1 is a side elevation of a stove pipe joint locked in position in a chimney flue by the use of this device.

Figure 2 is a view of the thimble alone.

The invention consists in forming a single piece of sheet metal into a thimble 1, forming an integral flange 2 around its inner 25 end for the purpose of holding the thimble in the flue 3, and then striking out a tongue 4 from the thimble, said tongue being cut free at the point 5 while remaining attached at the outer point 6; and then bending the 30 tongue outwardly and down upon the thimble to form a pipe holding element. A rivet 7 may be employed to bind the tongue securely to the thimble, and a hole 8 is pierced in the end of the tongue, through which a

wire 9 is run and secured around the elbow 35 10 of the stove pipe 11 to hold the pipe securely in position.

While we have herein described a certain specific method of constructing and assembling the elements of our invention, it is understood that same may be varied in minor details, not departing from the spirit of our invention as defined in the appended claims.

We claim:

1. A chimney thimble for stove pipes, comprising a single piece of sheet metal formed into a thimble, with a retaining flange at its inner end and having a pipe holding tongue struck out from the body of the 50 thimble, the said tongue being cut free inwardly of the thimble and remaining integrally attached outwardly of the thimble, the free end being bent outwardly and down upon the thimble.

2. In a thimble for stove pipes, an integral retaining flange formed around the inner end, and an integral pipe holding tongue at its outer end, the tongue being cut free and being bent outwardly and down 60 upon the thimble, and having a wire engaging hole at its free end.

LOUIS B. MALINOWSKY.
CLYDE W. KIRK.
